(57) CLAIM

The ornamental design for an electric nose hair trimmer, as shown and described.

DESCRIPTION

FIG. 1 is a front elevation view of an electric nose hair trimmer showing our new design;

FIG. 2 is a rear elevation view thereof;

FIG. 3 is a left side view thereof;

FIG. 4 is a right side view thereof;

FIG. 5 is a top plan view thereof;

FIG. 6 is a bottom plan view thereof;

FIG. 7 is a first perspective view thereof; and,

FIG. 8 is an enlarged view of the part designated as "8" in FIG. 7.

The evenly broken lines in the drawings illustrate portions of the article that form no part of the claim. The dot-dash lines shown from FIGS. 7 and 8 represent the designation of enlargement views and form no part of the claimed design.
